UNITED STATES PATENT OFFICE.

EDGAR E. BROSIUS, OF PITTSBURGH, PENNSYLVANIA.

CINDER-NOTCH STOPPER.

Application filed December 9, 1925. Serial No. 74,385.

The present invention relates broadly to an improved form of apparatus by means of which the cinder notch or cinder tap hole of a blast furnace is adapted to be closed or 5 opened at will, and more particularly to an improved form of mounting and operating mechanism for such an apparatus.

It has heretofore been proposed in the art to which the present invention relates to provide a furnace botting apparatus or cinder notch stopper of the type suspended from a suitable overhead support by a plurality of levers, one of the levers being of special construction and cooperating with pins and 15 slots in such manner as to slightly raise the rear end of the botting arm during backward movement thereof in order to cause the front of the botting arm to travel in a substantially straight line. Such constructions, 20 while effective generally for the purposes contemplated, have been objectionable due to mechanical difficulties involved in the construction and operation thereof.

It has also been customary in installations 25 of this character to utilize actuating means remotely positioned relative to the botting apparatus itself. This has necessitated special operating connections and special constructional features for each installation.

The present invention has for certain of 30 its objects to provide an improved apparatus of this general character such that a rigid and effective support for the botting arm is provided, the support being of such construction that the botting end of the arm is moved in a substantially horizontal plane 35 without sliding friction of the character heretofore necessitated.

Another object of the invention is to provide 40 an apparatus which is in effect self-contained, the actuating means constituting a component part thereof, and itself suspended or carried by the support for the botting arm.

In the accompanying drawings there are 45 shown, for purposes of illustration only, certain preferred embodiments of the present invention, it being understood that the drawings do not define the limits of my invention, 50 as changes in the construction and operation disclosed therein may be made without departing either from the spirit of the invention or the scope of my broader claims.

In the drawings:

55 Figure 1 is a combined sectional and side

elevational view, illustrating an improved cinder notch stopper constructed in accordance with the present invention in operative relation to a furnace;

Figure 2 is a sectional view on the line 60 II-II of Figure 1, looking in the direction of the arrows;

Figure 3 is a sectional view on the line 65 III-III of Figure 1, looking in the direction of the arrows;

Figure 4 is a sectional view on the line 70 IV-IV of Figure 1, looking in the direction of the arrows, the furnace not being shown in this figure;

Figure 5 is a view similar to Figure 1, 75 illustrating a modified form of the invention;

Figure 6 is a sectional view on the line 80 VI-VI of Figure 5, looking in the direction of the arrows;

Figure 7 is a view similar to Figure 5, 85 illustrating a slightly modified embodiment of the invention; and

Figure 8 is a detail elevational view of a portion of the front link structure.

The present apparatus, in accordance with this invention, is adapted for use with furnaces of usual construction embodying a cinder notch or a cinder tapping hole 2 which may be provided with the usual monkey cooler 3 and cinder monkey cooler 4.

Above the tapping hole 2 the furnace may be provided with a suitably constructed supporting band or girder 5 to which is attached a U-shaped yoke 6, as illustrated in detail in 90 Figure 4. Cooperating at one end with a yoke 6 is a horizontally extending beam structure 7 constituting an overhead support for the cinder notch stopper. The opposite end of the beam structure 7 extends below 95 the usual bustle pipe 8 and is secured thereto by straps 9 passing therearound. In order to permit the support 7 to be correctly adjusted horizontally and vertically to bring the parts of the apparatus into accurate 100 alignment with the cinder notch, the sides of the yoke 6 are provided with elongated openings 10 to receive bolts 11 passing therethrough, while the bottom of the yoke is provided with a similar opening 12 for the reception of a bolt 13. The bolt 13 is of such length that it is adapted to cooperate with shims 14, any desired number of which may be added or removed at will. This construction enables the yoke 6 to be firmly secured to 110

the blast furnace, and at the same time enables substantially universal adjustment of the support 7.

The apparatus may conveniently be constructed to comprise a botting arm 15 having one end shaped to provide an emergency sledging head 16 by means of which the bar may be moved by means of a sledge or the like should it become stuck to an extent to 10 require such measures. Projecting forwardly from the botting arm is a botting bar 17 on the front end of which is a stopper or bott 18 cooperating with the cinder monkey cooler.

15 The botting-arm is conveniently carried by a system of links, such system comprising a front link structure 19 and a rear compound link structure 20. The front link structure comprises spaced side arms cooperating at 20 their lower ends with a pivot pin 21 and at their upper ends with a pivot pin 22 extending through the support 7. Intermediate their ends the side arms carry a cross head 23 having a slot 24 through which 25 passes a transversely extending pin 25. The compound link structure for the rear of the botting arm comprises side arms having a pivotal connection 26 at their lower ends with the botting arm, and having upper pivotal connections 27 carried by the lower ends 30 of auxiliary links 28 and constituting, in effect, crank arms mounted at their upper ends on a common shaft 29 extending transversely of the support 7. By reason of this 35 construction, it will be apparent that by actuating the crank arms 28 the pivot points 27 about which the link structure 20 moves may be varied at will, thereby causing the rear end of the botting arm to travel through 40 any desired path. Inasmuch as it is desirable to have the front end of the botting arm travel in a substantially horizontal direction until it is clear of the furnace, it is necessary, during the rearward movement of 45 the apparatus, to gradually swing the crank arms 28 in a counter-clockwise direction, as viewed in Figure 1, thereby effecting a gradual raising of the rear end of the botting arm and a consequent lowering of the front 50 end thereof to compensate for the tendency of the link structure 19 to raise the botting arm.

For effecting the foregoing operation, there may be provided actuating means comprising a cylinder 30 having trunnions 31 journaled in bearings 32 carried by the support 7 and projecting downwardly therefrom. On the outer end of one of the trunnions 31 there is secured a gear segment 33, the teeth of which mesh with a pinion 34 on one end of the shaft 29. By reason of this construction, it will be apparent that tilting movement of the cylinder will be effective for imparting rotation to the pinion 34 and 60 consequently to the shaft 29 and crank arms 65

28. This movement bears a definite relation to the lengths of the link structures whereby the desired operating characteristics of the botting arm are obtained. Operatively carried by the cylinder 30 is a piston rod 35, 70 the front end of which is formed with an elongated eye 36 adapted to receive the pin 25. This pin and eye construction constitutes, in effect, a lost motion connection between the piston rod and the cross head 23 75 whereby rearward movement of the piston initially imparts no movement to the botting arm. At the end of the travel of the pin 25 in the eye 36, however, a sudden blow is imparted to the apparatus which is effective for releasing the same under all normal operating conditions, and thereupon continued travel of the piston rod 35 will be effective for moving the botting arm from the full line position illustrated in Figure 1 80 to the dotted line position. During this movement the cylinder will be caused to swing in a clockwise direction about its trunnions 31 due to the path of travel of the pin 25. This movement will in turn be effective 85 for moving the gear segment 33 in a clockwise direction for rotating the crank arms 28 in a counter-clockwise direction for thereby gradually lifting the pivotal supporting points 27 and consequently the rear end of 90 the botting arm.

As a safety measure, there may be provided a safety latch 37 having a pivotal mounting 38 on the front cylinder head 39, the safety latch comprising depending jaws 100 40 adapted to ride over a pin 41 projecting from opposite sides of the piston rod and thereby lock the same in the dotted line position of Figure 1. For releasing the apparatus, the latch is provided with an upwardly extending release arm 42 to which may be connected a cable 42' and running to the cast house wall whereby the apparatus may be released from a distance. It will be understood that the cylinder may be provided with 105 fluid connections 43 at the opposite ends thereof whereby fluid may be directed to or exhausted from the cylinder as required to effect operation of the piston rod 35.

It will be apparent to those skilled in the art that a compound link structure might be utilized for both ends of the botting arm to thereby obtain a modified path of travel of the bott, it only being necessary to so bodily move the effective supporting axis or axes 110 as to compensate for the normal tendency of the botting arm to rise due to the arcuate paths through which its supporting link structures move. In the interest, however, of simplicity of construction and operation, 115 a single compound link structure is in most cases preferable.

In Figures 5 and 6 of the drawings there is illustrated a slightly modified embodiment of the invention, showing another form 120

of compound link support. In these figures parts corresponding to parts already described are designated by the same reference characters having a prime affixed thereto. 5 In some blast furnaces the cooler 50, indicated in dotted lines in Figure 1, is projected outwardly a considerable distance beyond the furnace, as indicated, for example, in Figure 5. In such cases it may be desirable 10 to extend the length of movement of the bott in a substantially horizontal plane and then suddenly break the line of travel of the bott after it clears the cooler, to thereby permit it to move upwardly to a position in 15 which it is out of the way. In such cases the link structure 20' comprising the crank arms 28' may be of slightly modified construction. As illustrated in Figure 5, the crank arms 28' are not operatively connected 20 with the cylinder 30'. At least one of these arms, however, is extended rearwardly in substantial parallelism to the support 7' and carries at its outer end a counterweight 51, the counterweight tending normally to urge 25 the parts into the full line position indicated in Figure 5. Upon movement of the botting arm 15' backwardly under the influence of its actuating mechanism the link structure 19' operates in exactly the manner before described. The link structure 20', however, starts moving about the pivots 27', so that the rear end of the botting arm is caused to rise relatively faster than the front end and thereby compensate for the arc through 35 which the link 19' moves. During this movement the effectiveness of the counterweight is partly overcome to the extent that the pivots 27' move from their full line position to their dash-and-dot position of Figure 5. At this time the U shaped projection 52 constituting an integral part of the crank arms 28' occupies the position illustrated in chain lines in Figure 5 in engagement with the link structure 19'. Continued 40 movement of the botting arm is effective through the projection 52 for quickly moving the pivotal points 27' from their chain line position to their dotted line position, thereupon causing movement of the botting 45 arm, botting bar and bott from the chain line position to the dotted line position. It will be apparent from the drawings, however, that this rapid movement of the pivot points 27' does not occur until after the bott 50 has cleared the cooler. The movement is obviously effective for relatively lengthening the link structure for the rear of the botting arm, which in turn tends to quickly raise the bott and upon continued movement carry 55 the apparatus to an upper position in which it is entirely out of the way.

During the return movement of the parts the counterweight tends to swing the crank arms 28' from the dotted line position to the 60 chain line position as rapidly as permitted

by the projection 52. After the projection 52 leaves the link structure 19', the parts move from the chain line position into the full line position, causing the bott to again travel in a substantially horizontal plane 70 into operative position with respect to the cinder monkey cooler.

In Figures 7 and 8 there is illustrated an embodiment of the general character shown in Figures 5 and 6, and parts corresponding to parts therein are designated by the same reference characters having the prime omitted and one hundred (100) added thereto. In accordance with this embodiment, the U-shaped projection 52 is omitted, and its function accomplished by a trip rod 60 operatively connected at one end to the pivots 127, and at the opposite end slidably mounted in a pin 61 rotatably carried in bearings 62 in the cross head 123. At an intermediate 85 point the trip rod is provided with a stop or shoulder 63, and intermediate this stop is a compression or buffer spring 64.

With this construction the operation is similar to that before described, rotation of 90 the rear link structure 120 continuing about the pivots 127 until the movement of the parts brings the end of the compression spring 64 into contact with the stop 63. Thereafter continued movement will break 95 the joint between the link structure 120 and the crank arms 128, as before set forth. The buffer spring relieves the parts of the jar to which they are subjected by a construction as shown in Figure 5.

In all embodiments of the invention the structure is such that the crank arms change the effective position of the axis or pivots carried thereby, the crank thereupon compensating the normal tendency of at least 105 the front end of the botting arm to move upwardly. This construction, embodying a shaft pivot in at least one of the link supports, has been found to be highly desirable.

Certain advantages of the present invention arise from the provision of a compound link support for at least one end of a botting arm, the support being of such construction that the effective pivotal axis of the supporting links is varied during the operation 110 of the apparatus to thereby cause the bott to travel in the desired direction.

Further advantages arise from the provision of actuating means in the form of a cylinder of such construction that it is both effective for imparting a jar to the bott for loosening the same from the monkey and for effecting a change in the position of the axis of at least one of the supporting means.

Still further advantages arise from the 125 manner of carrying the overhead support whereby it may be substantially universally adjusted to bring the bott into the exact position required, thereby facilitating installation of the apparatus and enabling accu- 130

rate adjustment as required by continued use.

Additional advantages are inherent in the utilization of actuating means constituting a component part of the apparatus and suspended from the bustle pipe or otherwise carried by the overhead support in proximity to the parts which it operates.

I claim:

10 1. In an apparatus of the character described, a botting arm, supporting means for the front end of said arm, a compound link support for the rear end of said arm, and means for changing the relative relationship of the parts of said compound link support about pivotal axes only during backward movement of said arm for changing the path of travel of the rear end of said arm to effect movement of the front 20 end in a substantially horizontal plane.

2. In an apparatus of the character described, a botting arm, link supporting means for the front end of said arm, a compound link support for the rear end of said arm, and actuating means for simultaneously moving said botting arm backwardly and changing the relative relationship of the parts of said compound support about pivotal axes only for changing the path of 30 travel of the rear end of said arm.

3. In an apparatus of the character described, a botting arm, supporting means therefor, actuating means therefor, and a lost motion connection between the botting 35 arm and actuating means for imparting a jar for loosening the botting arm when the actuating means is operated in one direction.

4. In an apparatus of the character described, a botting arm, supporting means therefor, actuating means therefor, and a lost motion connection between the botting arm and actuating means for imparting a jar for loosening the botting arm when the 45 actuating means is operated in one direction, said actuating means comprising a cylinder and piston.

5. In an apparatus of the character described, a bott, power actuating means for said bott, and means connecting the power actuating means and bott for imparting a jar to the bott upon operation of the actuating means.

6. In an apparatus of the character described, a botting arm, a supporting link for the front end of said arm, a supporting link for the rear end of said arm, a crank to which said last mentioned supporting link is pivotally connected, and means for 60 moving said crank during rearward movement of the arm for gradually raising the pivotal point about which said last mentioned link is effective.

7. In an apparatus of the character described, a botting arm, a supporting link

for the front end of said arm, a supporting link for the rear end of said arm, a crank to which said last mentioned supporting link is pivotally connected, and means for moving said crank during rearward movement of the arm for gradually raising the pivotal point about which said last mentioned link is effective, said means comprising a pivotally supported actuating cylinder operatively connected to said botting 75 arm.

8. In an apparatus of the character described, a botting arm, a support for the front end of said arm, a link operatively connected to the rear end of said arm, a crank to which the upper end of said link is pivotally connected, and means effective upon rearward movement of said arm for gradually raising said pivotal connection. 80

9. In an apparatus of the character described, a botting arm, a support for the front end of said arm, a link operatively connected to the rear end of said arm, a crank to which the upper end of said link is pivotally connected, and means effective 85 upon rearward movement of said arm for gradually raising said pivotal connection, said means comprising a pivotally mounted actuating cylinder.

10. Apparatus of the character described, comprising a support, a botting arm carried thereby, and means for vertically and horizontally adjusting one end of said support. 95

11. A cinder notch stopper, comprising a support, a botting arm carried thereby, and actuating means for said botting arm, said actuating means comprising a cylinder and piston pivotally mounted on said support. 100

12. A cinder notch stopper, comprising a support, a botting arm carried thereby, and actuating means for said botting arm, said actuating means comprising a cylinder and piston pivotally mounted on said support, a lost motion connection between said piston and botting arm for imparting a jar to the botting arm upon movement of the piston in one direction. 110

13. In an apparatus of the character described, a botting arm, link supporting structures for opposite ends of said arms, one of said structures being of compound nature comprising one portion effective as a crank and another portion effective as a link, and means operative upon initial rearward movement of said botting arm for effecting relative movement between said crank and link for compensating the normal tendency of the front end of said botting arm to move upwardly. 115 120

14. In an apparatus of the character described, a botting arm, link supporting structures for opposite ends of said arms, at least one of said structures being of compound nature comprising one portion effec- 125 130

tive as a crank and another portion effective as a link, and means operative upon initial movement of said botting arm in either direction to effect relative movement 5 between said crank and link to vary the normal path of travel as defined by said link supporting structures moving about its axes.

15. In an apparatus of the character described, a botting arm, link supporting 10 structures for opposite ends of said arms, at least one of said structures being of compound nature comprising one portion effective as a crank and another portion effective as a link, means pivotally connecting said 15 portions to permit relative movement therebetween, and means operative upon initial rearward movement of said botting arm for changing the effective position of the axis about which such compound link structure 20 is operative.

16. In an apparatus of the character described, a botting arm, link supporting 25 structures for opposite ends of said arms, at least one of said structures being of compound nature comprising one portion effective as a crank and another portion effective as a link, means pivotally connecting said portions to permit relative movement there- 30 between, and means operative upon initial movement of said botting arm in either direction for causing movement of said crank arm to change the effective position of the axis carried thereby.

17. In an apparatus of the character de- 35 scribed, a botting arm, link supporting structures for opposite ends of said arms, at least one of said structures being of compound nature comprising one portion effective as a crank and another portion effective as a link, and means operative upon initial movement of said botting arm for caus- 40 ing said crank to compensate the normal ten- dency of at least the front end of said botting arm to move upwardly.

18. In an apparatus of the character de- 45 scribed, a botting arm, a plurality of link

supports for said arm, one of said link supports comprising relatively movable parts, and a shifting pivot in said last mentioned link supports pivotally connecting the parts 50 thereof.

19. In an apparatus of the character de- 55 scribed, a botting arm, a plurality of link supports comprising relatively movable parts, a shifting pivot in said last mentioned link supports pivotally connecting the parts thereof, and means for shifting said pivot.

20. In an apparatus of the character de- 60 scribed, a botting arm, a plurality of link supports of substantially equal length for said arm, and means for causing the supporting ends of said links to travel in arcs of different radii during at least part of their movement, said means comprising relatively movable parts in one of said supports and a shifting pivot in pivotally connecting said parts.

21. In an apparatus of the character de- 70 scribed, a botting arm, a support for the front end of said arm, a link operatively connected to the rear end of said arm, means for effecting movement of said arm into and out of operative position, and means pivotally cooperating with said link and effective 75 before conclusion of the movement of the arm into inoperative position for changing the normal arc of travel of at least one end of said link.

22. In an apparatus of the character de- 80 scribed, a botting arm, a plurality of link supports for said arm, a shifting pivot in and connecting relatively movable parts of at least one of said link supports, means for gradually shifting said pivot during one 85 portion of the movement thereof, means for suddenly shifting said pivot during another portion of such movement.

In testimony whereof I have hereunto set my hand.

EDGAR E. BROSIUS.
